UNITED STATES PATENT OFFICE.

WILLIAM C. EDWARDS, JR., OF KANSAS CITY, MISSOURI.

REINFORCEMENT AND CENTERING.

1,094,985.

Specification of Letters Patent. Patented Apr. 28, 1914.

Application filed January 6, 1914. Serial No. 810,686.

To all whom it may concern:

Be it known that I, WILLIAM C. EDWARDS, Jr., a citizen of the United States, residing at Kansas City, in the county of Jackson and State of Missouri, have invented certain new and useful Improvements in Reinforcement and Centering, of which the following is a clear and accurate description, reference being had to the accompanying drawings.

My invention relates to a combined form and reinforcement useful in the construction of monolithic concrete walls, tanks, silos, grain bins, etc.

The principal advantages attained are; a rigid metallic structure adapted to act as a form into which wet concrete may be deposited and tamped, the exterior surfaces of the structure having projecting horizontal corrugations which support outer plastic coatings of cement mortar and provide means for the easy erection and combination of the several individual sections composing the complete structure; a very dense concrete wall since tamping will drive out any air, mixed in the concrete, through the perforated openings in the sides of the reinforcement; perfect reinforcement for such structures.

Similar numerals of references designate corresponding parts in the several figures of the drawings.

Figure 1. represents a partially completed concrete tank showing the assembled sections in combination, concrete within the compartments thus formed, and outer plastered surfaces. Fig. 2. shows a view in perspective of a sheet metal section showing the stud and side members and the parallel horizontal corrugations reversed in position intermediate their ends. Fig. 3. is a plan view of a single section of expanded metal employed in the tank construction seen in Fig. 1. Fig. 4. is a side view of the section seen in Fig. 3. Fig. 5. is an end view of the section seen in Fig. 3. Fig. 6. represents a fragmentary portion of a sheet of metal, slitted and ready for expansion; a single diamond produced by the expansion of adjacent strands; and the approximate return of these strands to their original position shown in the slitted sheet for the pur-

pose later described and as shown in Fig. 5. Fig. 7 shows a view in perspective of several sections, similar to the one shown in Fig. 2., in combination, and concrete within the compartments thus formed. Fig. 8 represents a cross sectional view taken along the line $x-x$ Fig. 3. Fig. 9 represents a cross sectional view taken along the line $z-z$ Fig. 3. Fig. 10 represents a vertical section taken along a stud 11 in Fig. 1.

By reference to the several drawings, 11 represents a stud formed in a sheet between two side members 12 and 12. Corrugations 13 are formed lengthwise of the sheet, being reversed intermediate their ends at or in the stud so that said corrugations 13 project outwardly beyond the planes of the side members 12 to form outer shelves or ledges 70 as clearly seen in Figs. 1, 2, 4, 5 and 7. These corrugations serve to stiffen the side panels 12 materially in the combined form and reinforcement seen in Figs. 1 and 7, to support the finish cement plaster coating 75 applied on the exterior surfaces; and to unite the combined sections.

Where sheet steel is employed, the corrugations are preferably reversed intermediate their length as seen at 14. Fig. 2. so that 80 when the sheet is bent at 20, 20, and 20', 20', and the stud 11 is thereby formed between the two side members 12 and 12, said corrugations will project outwardly from said stud and along the outer surfaces of said side members.

Figs. 3, 4 and 5 show a single section of expanded metal in which the corrugations 13 are formed on reverse sides of the sheet.

Fig. 6 shows at 15 a fragmentary portion 90 of sheet metal, slitted ready for expansion. At 16 a single diamond formed by the expansion of adjacent strands in 15 is shown. It will be seen at 17 that this diamond may be lengthened or stretched to a long diamond 95 by forces acting in the direction of the arrows, thus serving to contract the points 18 and 19 of the diamond.

In forming the corrugations 13 in a section, shrinkage occurs in the width of a 100 section. As seen in the section of sheet metal, Fig. 2. and is previously explained, the corrugations 13 reverse at 14 in the stud 11, thus the height of the stud 11 is

the same as the height of the sides 12 and 12. By reference to Figs. 3, 4 and 5 it will be noted that the stud member 11 is not corrugated and still the height of the 5 stud 11 is made equal to the height of the corrugated side members 12 and 12. In forming the corrugations 13, 13 Figs. 3, 4, and 5 on opposite sides of the sheet, opposite forces act on the strands of expanded 10 metal connecting 20, 20 Fig. 4 in the manner shown by the arrows in Fig. 6 and as described concerning, so that the diamonds of expanded metal are stretched or lengthened as seen at 21 Fig. 5, the sides of the 15 diamonds 21 being thus contracted so that the height of the stud 11 is caused to shrink with the corrugated side members 12 and 12 of the section.

Fig. 1. shows a series of combined sections as illustrated in Figs. 3, 4 and 5. The sides 12 and corrugations 13 being curved to proper radii for the tank structure. The sections are combined as seen in Figs. 1 and 7 by shingling the end portions 22-23 of 25 the corrugations 13 of the sections over the adjacent intermediate portions 20-24 of the corrugations 13 on adjacent sections, thus providing compartments or molds 25 formed by the opposite sides 12 and 12 and 30 studs 11 and 11 of the combined sections.

While any type of corrugation may be used, preference is given to the dovetail type illustrated. The dovetail or contracted type of corrugation is of particular advantage 35 in assembling over other types since it can be easily snapped together at these interfitting parts and assists in preventing disengagement during erection and placing of the concrete. Fig. 10 shows a vertical section 40 taken along a stud member 11 in Fig. 1. The stud 11 is thus disclosed just as represented in Fig. 5 and shows end portions (x-x Fig. 8 and z-z Fig. 9) of two adjacent sections shingled thereon for the purposes previously 45 described. The portions 22-23 of the corrugations 13 are preferably slightly larger in cross section than the portions 20-24. A pin, wire or clip may be fastened through the interlocked corrugations 50 at 26 Fig. 1. and serve further to prevent disengagement.

Such other modifications may be employed as are within the scope of the appended claims.

Having described my invention what I now claim as new and desire to secure by Letters Patent is:

1. Reinforcement for concrete construction comprising a metal sheet having two 60 side members extending in opposite directions from opposite sides of an intermediate transverse stud portion of said sheet; longitudinal corrugations formed in said sheet transverse to the stud, each corrugation being reversed at the stud thereby sepa-

rating said corrugation into two portions lying respectively on the outer surfaces of the side members of the sheet.

2. Reinforcement for concrete construction comprising a metal sheet having two 70 side members extending in opposite directions from opposite sides of an intermediate transverse stud portion of said sheet; longitudinal corrugations formed in said sheet transverse to the stud, each corrugation being reversed at the stud thereby separating 75 said corrugation into two portions lying respectively on the outer surfaces of the side members; such corrugations being slightly larger in cross section at their outer ends 80 than they are adjacent the stud.

3. Reinforcement for concrete construction comprising combined sections of metal 85 sheets; each section having two side members extending in opposite directions from opposite sides of an intermediate transverse stud portion of said section; longitudinal corrugations formed in said sheet transverse to the stud, each corrugation being reversed at the stud thus separating said corrugation into two portions lying respectively on the outer surfaces of the said side members; the ends of such corrugations being shingled over and engaged with intermediate portions of similar corrugations 90 adjacent the studs on adjacent sections, to form compartments.

4. Reinforcement for concrete construction comprising an expanded metal sheet having two side members extending in opposite directions from opposite sides of an intermediate transverse stud portion of said expanded metal sheet; longitudinal corrugations formed in said sheet transverse to the stud, each corrugation being reversed at 100 the stud thereby separating said corrugation into two portions lying respectively on the outer surfaces of the side members of the sheet.

5. Reinforcement for concrete construction comprising combined sections of expanded metal sheet; each section having two side members extending in opposite directions from opposite sides of an intermediate transverse stud portion of said expanded metal section; longitudinal dovetail corrugations formed in said sheet transverse to the stud, each corrugation being reversed at the stud separating said corrugation into two portions lying respectively on the outer surfaces of the said side members; such corrugations being slightly larger in cross section at their outer ends than they are at the intermediate portions adjacent the stud, such outer enlarged ends being shingled over and engaged with intermediate portions of similar corrugations, on adjacent sections, to form compartments.

6. Reinforcement for concrete construction comprising an expanded metal sheet 120

having two side members extending in opposite directions from opposite sides of an intermediate transverse stud portion of said sheet; longitudinal corrugations formed in said sheet, each corrugation being reversed adjacent the stud separating said corrugation into two portions lying respectively in the side members of the sheet; the mesh in

the stud connecting said two portions of such longitudinal corrugation having less ¹⁰ expansion than the remainder of the mesh in said stud.
